UNITED STATES PATENT OFFICE.

ARTHUR CECIL BUTLER, OF BOSTON, MASSACHUSETTS.

DRAWING MECHANISM.

Application filed September 16, 1922. Serial No. 588,582.

To all whom it may concern:

Be it known that I, ARTHUR CECIL BUTLER, a subject of the King of Great Britain, residing at Boston, in the county of Suffolk and State of Massachusetts, have invented new and useful Improvements in Drawing Mechanism, of which the following is a specification.

This invention relates to mechanism for drawing fibrous material such as rovings, slivers and the like. Such mechanisms ordinarily comprise sets of rollers or other traveling surfaces between the nips of which the roving passes, successive sets of rollers being driven at progressively higher surface velocities so as to draw out and attenuate the roving. In connection with these rollers or other surfaces it has been proposed to employ friction plates between which and the surfaces the roving passes. The proper distances between the nips of successive sets of rollers varies with the length of staple being drawn and it is therefore desirable to provide for relative adjustment of these rollers.

The present invention provides a construction in which such adjustment may be effected, but at the same time permits the retarding plate to project closely toward the nip of the succeeding pair of rollers to properly direct the roving thereto quite irrespective of the positions of the adjusted rollers.

For a more complete understanding of this invention reference may be had to the accompanying drawings showing certain constructions embodying the invention by way of example in which

Figure 1 is a somewhat diagrammatic side elevation of one embodiment.

Figure 2 is a fragmentary plan of the same the upper rollers being removed.

Figure 3 is a detail of one of the retarding plates.

Figures 4 and 5 are views similar to Figures 1 and 2, but showing a modified construction.

Referring first to Figures 1, 2, and 3, 1 indicates one of a series of spaced roller 50 stands each having a journal at its forward end for a forward lower roller 2. Rearwardly of this roller a bracket 3 is adjustably fixed so as to be moved toward and from the roller 2, this bracket having journaled therein an intermediate lower roller 4. Rearwardly of this bracket is a bracket

5 in the forward portion of which is journaled a lower roller 6. The bracket 5 also carries pivoted thereto the rear end of a cap bar 7 which projects forwardly over the roller stand and is adjustable in length as by means of a bolt and slot connection between its forward and rear parts as indicated at 8. The forward end of this bar 7 has guides for the slidable reception of journals on an upper forward roller 9 which cooperates with the lower roller 2 to form a nip for the passage of the roving. Above the roller 6 the bar 7 is provided with a guide for the reception of a trunnion of a roller 10 which cooperates with the roller 6 to form a rear nip through which the roving passes. To the rear of the rollers 6 and 10 is mounted a traverse bar 11 which is traversed back and forth in a manner well known in the art to effect a travel of the roving lengthwise of the nips between the various rollers. The bracket 5 may be adjustable toward and from the bracket 3 by means of a bolt and slot connection shown at 12. The bracket 3 may be adjusted while the machine is running to space the roller 4 relative to the rollers 2 and 9 by means of a rock shaft 13 having a pin 14 thereon entering a slot 15 in the bracket. The shaft 13 may be rocked by any suitable means and as herein shown a worm segment 16 is fixed thereto and meshing therewith is a worm 17 fixed to a shaft 18 which may be turned by means of a hand wheel 19. Co-operating with the roller 4 is a retarder plate 20 shown detached in Figure 3. This plate 20 has an intermediate flat portion 21 which rests on the roving as it passes over the roller 4. The forward edge of the plate 20 is inclined downward slightly at either end as shown at 22 and is provided with a roving guide formed by a slot 23. Between the slots the plate 20 may have portions 24 integral therewith downwardly bent to engage the roller 2 at its rear so as to prevent the portions 22 from being caught between the nip of the rollers 2 and 9 but permitting these portions to approach closely thereto. Between the down turned portions 24 the plate 20 may have a forwardly projecting tongue 25 which may rest on a reduced portion 26 of the roller 2 as shown in Figure 2. The rear edge of the plate 20 is downwardly turned and has therein notches 30 forming roving guides in alinement with the notches 23. Between the notches the plate

20 may have a rearwardly projecting tongue 31 which rests on a reduced portion 32 of the roller 6. If desired the rear end of this tongue may be turned downwardly as shown 5 at 34 in Figure 3 to engage the rear portion of the roller 6. This turned down portion may be used in place of the portions 24, which may be then omitted, to hold the plate from being caught between the rollers 2 and 10 9, or it may be omitted and the turned down portions 24 relied on instead.

With this construction it will be seen that the lower intermediate roller 4 may be adjusted toward and from the nip between the 15 front rollers 2 and 9 without disturbing the plate 20 which is maintained at all times in position to direct the roving closely into the nip between the forward rollers. While as shown there is no connection between the 20 plate 20 and the traverse bar, the engagement of this plate on the rovings being relied upon to give it its traversing movement, if desired, the tongue 31 might be prolonged 25 into engagement with the traverse bar 11 as shown in Figure 2. Ordinarily, however, this is not deemed necessary.

In Figures 4 and 5 an arrangement employing five rows of rollers is shown. Referring to these figures the roller stand is indicated at 50 and carries at its forward end the forward roller 51. Cooperating with this roller is an upper roller 52 having trunnions guided in a cap bar 53 which is hinged at 54 to a bracket 55 adjustably supported 35 at the rear end of the stand similar to the bracket 5 of the first form described. Back of the front roller 51 is mounted a slideable bracket 56 which is adjustable toward and from the front roller 51 by means of a rock 40 shaft 57 having a pin 58 therein engaging a slot 59 in the bracket similar to the mounting and method of adjustment of the bracket 3 shown in Figure 1. Any suitable means may be employed to rock this shaft, as, for example, worm and segment mechanism such as is shown in Figure 1. The bracket 56 has journaled therein a front intermediate lower roller 60, a central intermediate lower roller 61 and has adjustably fixed thereto a bracket 50 62 in which is journaled a rear intermediate roller 63. Means for adjusting this bracket 62 similar to that for adjusting bracket 56 may be provided if desired. Back of the bracket 56 and journaled in the forward end 55 of the bracket 55 is a rear lower roller 64. Resting on this roller is an upper roller 65 having trunnions journaled in vertical guides in the cap bar 53, while cooperating with the rollers 60 and 61 is a roller 66 60 which extends between the cap bars of two spaced stands but is not otherwise guided thereby. Pressure may be exerted downwardly on the rollers 65 and 66 and for this purpose a bar 67 is shown which engages over reduced portions 68 and 69 of the roll-

ers 65 and 66 and may have hung thereover a link 70 to which a weight or spring may be applied.

Cooperating with the front and rear rollers 60 and 63 is a retarding plate 75. The rear portion of this plate comprises a substantially flat portion 76 having ears 77 extending therefrom closely adjacent the nip between the intermediate upper and lower rollers 66 and 61, these ears having slots 78 75 therein to serve as roving guides. The rear end of the portion 76 is downwardly bent as shown at 79 and may also have roving guide slots 80 in alignment with the guide slots 77. By this construction the bracket 62 may be 80 adjusted toward and from the roller 61 without in any way changing the position of the plate 75 so that the ears 77 may extend closely adjacent the nip between the rollers 61 and 66 without danger of being seized 85 thereby. Forwardly of the portion 76 the plate 75 has a narrow tongue portion 85 which passes over a reduced portion 86 of the lower roller 61 and carries at its forward end a wider portion 88 resting on the forward portion of the roller 60. This portion 88 preferably has ears 89 having roving guide slots 90 therein positioned closely adjacent the nip between the front rollers 51 and 52. The portions 88 and 85 of this plate 95 are so shaped as to embrace the roller 60 to such an extent as to move therewith so that as the bracket 56 is adjusted the three intermediate lower rollers, the upper intermediate roller and the retarder plate move as a unit and the portions 89 move toward and from the nip between the rollers 51 and 52. The plate, however, is held against forward and backward movement relative to the rollers 61 and 66 by its engagement over the 100 roller 60 so that the relationship of the ears 77 to the nip between the rollers 71 and 66 is not changed by adjustment of the roller 63. In this form also a traverse bar is shown at 95 having roving guides 96 therein. 105

Having thus described certain embodiments of this invention it should be evident to those skilled in the art that many changes and modifications might be made therein without departing from its spirit or scope 115 as defined by the appended claims.

I claim:

1. In a drawing mechanism, a pair of cooperating rollers through the nip of which a roving may pass, a roller adjustable toward and from said nip, and a retarder plate cooperating with said roller in all positions of its adjustment and projecting closely to the nip between said pair of rollers to an extent independent of the position of said roller. 120
2. In a drawing mechanism, a pair of cooperating rollers through the nip of which a roving may pass, a roller positioned at the rear of said nip, a retarding plate cooperating with said roller and acting to present the 125

roving to said nip, and means for adjusting said roller relative to said plate toward and from said nip.

3. In a drawing mechanism, a pair of cooperating rollers through the nip of which a roving may pass, a roller positioned at the rear of said nip, a retarding plate cooperating with said roller and acting to present the roving to said nip, and means for adjusting said roller relative to said plate toward and from said nip while the mechanism is running.

4. In a drawing mechanism, a pair of cooperating rollers through the nip of which a roving may pass, a lower roller positioned to the rear of said nip and adjustable toward and from said nip, a retarding plate resting on the roving passing over said lower rollers, and means for holding said plate with its forward edge closely adjacent said nip regardless of the position of adjustment of said lower roller.

5. In a drawing mechanism, a pair of cooperating rollers through the nip of which a roving may pass, a lower roller positioned to the rear of said nip and adjustable toward and from said nip, a retarding plate resting on the roving passing over said lower rollers, and means for holding said plate with its forward edge closely adjacent said nip regardless of the position of adjustment of said lower roller, said forward edge being provided with a roving guide.

6. In a drawing mechanism a pair of cooperating rollers through the nip of which a roving may pass, a lower roller positioned to the rear of said nip and adjustable toward and from said nip, a retarding plate having a flat portion resting on the roving passing over said lower roller, and means for holding said plate with its forward edge closely adjacent said nip regardless of the position of adjustment of said lower roller.

7. In a drawing mechanism, a pair of cooperating rollers, three rollers in series back of the nip between said cooperating rollers, a roller cooperating with the front and a middle roller of said three rollers to form nips through which a roving may pass, and a retarding plate acting to press the roving against the front and rearmost of said three rollers.

8. In a drawing mechanism, a pair of cooperating rollers, three rollers in series back of the nip between said cooperating rollers, a roller cooperating with the front and a middle roller of said three rollers to form nips through which a roving may pass, a retarding plate acting to press the roving against the front and rearmost of said three rollers, and means to adjust said three rollers and plate as a unit toward and from the nip between said cooperating rollers.

9. In a drawing mechanism, a pair of cooperating rollers, three rollers in series back

of the nip between said cooperating rollers, a roller cooperating with the front and middle roller of said three rollers to form nips through which a roving may pass, a retarding plate acting to press the roving against the front and rearmost of said three rollers, and means by which said rearmost roller may be adjusted relative to said plate toward and from the nip between said middle and its cooperating roller.

10. In a drawing mechanism, a pair of cooperating rollers, three rollers in series back of the nip between said cooperating rollers, a roller cooperating with the front and a middle roller of said three rollers to form nips through which a roving may pass, a retarding plate acting to press the roving against the front and rearmost of said three rollers, means to adjust said three rollers and plate as a unit toward and from the nip between said cooperating rollers, and means by which said rearmost roller may be adjusted relative to said plate toward and from the nip between said middle and its cooperating roller.

11. A drawing mechanism comprising front and rear pairs of cooperating upper and lower rollers through the nips between which a roving may pass, three intermediate lower rollers, an upper intermediate roller resting on the roving as it passes over the middle and front intermediate lower rollers, a retarding plate cooperating with the front and rearmost intermediate rollers, and means for applying pressure to certain of said upper rollers.

12. A drawing mechanism comprising front and rear pairs of cooperating upper and lower rollers through the nips between which a roving may pass, three intermediate lower rollers, an upper intermediate roller resting on the roving as it passes over the middle and front intermediate lower rollers, a retarding plate cooperating with the front and rearmost intermediate rollers, a bar resting on the rear and intermediate upper rollers, and pressure applying means acting on said bar.

13. A drawing mechanism comprising a plurality of rollers, and a retarding plate cooperating with two of said rollers, one of said two rollers being adjustable toward and from the other of said two rollers and relative to said plate.

14. A drawing mechanism comprising a plurality of rollers, a retarding plate cooperating with two of said rollers, said plate being formed to engage one of said rollers, and having a flat portion cooperating with the other of said two rollers, said other roller being adjustable toward and from said one roller and relative to said plate.

In testimony whereof I have affixed my signature.

ARTHUR CECIL BUTLER.
